GOLF CLUB HEAD

Ernest Sprinkel, 938 W. Rosewood Court,
Ontario, Calif. 91762

Filed Nov. 15, 1966, Ser. No. 4,681

Term of patent 14 years

(Cl. D34—5)

The broken line showing of a golf club handle in FIGURES 1, and 3-6 is for illustrative purposes only.

I claim:

The ornamental design for a golf club head, as shown and described.
